UNITED STATES PATENT OFFICE.

ARNOLD BJEKAAS, OF LONG PRAIRIE, MINNESOTA.

SHORT-TURNING GEAR.

1,298,650.

Specification of Letters Patent.

Patented Apr. 1, 1919.

Application filed January 24, 1917. Serial No. 144,189.

To all whom it may concern:

Be it known that I, ARNOLD BJEKAAS, a citizen of the United States, residing at Long Prairie, in the county of Todd, State 5 of Minnesota, have invented certain new and useful Improvements in Short-Turning Gears; and I do hereby declare the following to be a full, clear, and exact description of the invention, such as will enable others 10 skilled in the art to which it appertains to make and use the same.

This invention relates to improvements in running gear and particularly to short turning gear for large and heavy vehicles and 15 machines.

One object of the present invention is to provide a novel and simple device of this character whereby the rear wheels of a heavy machine, such as a threshing machine, can 20 be turned to permit the machine to be manipulated within a short space.

Another object is to provide a device of this character which will not be liable to displacement or derangement, and which 25 will not operate of itself.

Other objects and advantages will be apparent from the following description when taken in connection with the accompanying drawing.

30 In the drawing:

Figure 1 is a top plan view of the running gear equipped with my invention.

Fig. 2 is a sectional view taken on the line 2—2 of Fig. 1.

35 Fig. 3 is a sectional view taken on the line 3—3 of Fig. 1.

Fig. 4 is a sectional view taken on the line 4—4 of Fig. 1.

Referring particularly to the accompanying drawing 10 represents the front axle of the running gear, 11 the rear axle, and 12 the stub axles which are pivoted on the ends of the rear axle, as shown at 13. Extending forwardly of the axles 12, and forming integral parts thereof, are the arms 14, while similar arms 15 extend rearwardly therefrom, at points directly in rear of the first arms. The ends of these arms are formed with openings 16, as clearly seen 45 in the plan view, Fig. 1. On each side of the center of the rear axle, and forwardly and rearwardly thereof, are the brackets 17, in each of which is mounted a grooved roller 18.

50 Mounted on the center of the upper face of the front axle is a circular plate 19, in

the center of which is formed an opening 20 for the passage of the king bolt 21. Rotatably disposed on this plate is a second circular plate 22, also formed with an opening 23 for the bolt 21. On the upper plate, and secured thereto and to the vehicle or machine, is a block 24. Secured to this block is a casting 25, provided with the bearing eyes 26 for the reception of the shaft 27 which extends forwardly to a point within convenient reach for steering where it is provided with a crank handle 28 for turning the shaft. Mounted in the ears 29 of the casting is a shaft 30, carrying thereon 70 a worm wheel 31, which meshes with the worm 32 on the adjacent end of the shaft 27. Rigidly secured to the worm wheel is a grooved drum 33 around which the intermediate portion of a cable 34 is passed a 75 couple of turns. The ends of this cable extend rearwardly from the drum and engage around the rear rollers 18 and then toward the ends of the rear axle where they are secured in the eyes of the rearwardly extending arms 15. Secured to each portion of the cable, at points intermediate the axles, are cables 35 each one of which passes around one of the pulleys or grooved wheels 18, and is connected to an eye in one of the 80 forwardly extending arms 14.

Thus when the shaft 27 is turned in one direction, by means of the crank handle, one end of the cable 34 will be pulled and the other end slackened, while one of the 90 cables 35 will be correspondingly pulled and the other one slackened, thereby swinging one of the stub axles forwardly and the other one rearwardly. The size of the arc through which the stub axles are swung will 95 govern the arc of movement of the rear of the vehicle or machine, and the space in which the same can be turned. The worm wheel and worm cannot be moved by any pulling directly from the cables, thus insuring the perfect stability and rigidity of the structure.

The gear can be easily and conveniently manipulated from the driver's seat, and is readily adaptable for use on ordinary road 105 vehicles, or for heavy vehicles such as traction engines, threshing machines, and the like.

What is claimed is:

A short turning gear including a front 110 axle and a rear axle, stub axles mounted for pivotal movement on the ends of the rear

axle, grooved wheels mounted on the intermediate portion of the rear axle, a bracket mounted on the bolster of the front axle, a winding drum mounted in the bracket, the 5 stub axles having forwardly and rearwardly extending arms, a cable having its intermediate portion engaged several times around the drum and having its ends engaged around certain of the grooved wheels 10 and connected to certain of the arms of the stub axles, additional cables connected to

the remaining arms and engaged around the remaining grooved wheels and being secured to portions of the first cable, and means for rotating the said drum. 15

In testimony whereof, I affix my signature, in the presence of two witnesses.

ARNOLD BJERKAAS.

Witnesses:

HELEN SMITH,
L. J. RAMSTÖD.
